CLAIM

The ornamental design for an abrasive stone, as shown and
described.

DESCRIPTION

FIG. 1 is a right side elevational view of an abrasive stone,
showing my new design, wherein the left side elevational
view is a mirror image thereof;

FIG. 2 is a top plan view thereof;

FIG. 3 is a bottom plan view thereof; and,

FIG. 4 is an end elevational view thereof, wherein the
opposite end view is identical.
